No. 732,446.

PATENTED JUNE 30, 1903.

H. RIPLEY.

CARPET STRETCHER.

APPLICATION FILED JUNE 21, 1902.

NO MODEL.

UNITED STATES PATENT OFFICE.

HENRY RIPLEY, OF KEENE, NEW HAMPSHIRE.

CARPET-STRETCHER.

SPECIFICATION forming part of Letters Patent No. 732,446, dated June 30, 1903.

Application filed June 21, 1902. Serial No. 112,721. (No model.)

To all whom it may concern:

Be it known that I, HENRY RIPLEY, a citizen of the United States, residing at Keene, in the county of Cheshire and State of New Hampshire, have invented a new and useful Carpet-Stretcher, of which the following is a specification.

This invention relates generally to carpet stretchers, and more particularly to one employing a pawl-and-ratchet lever-operated mechanism for the purpose of drawing a toothed stretching-bar toward an adjacent side of the room.

The object of the invention is to provide an exceedingly simple, compact, and durable construction of stretcher which can be quickly and easily set in place and operated to accomplish the operations heretofore mentioned; and with this object in view the invention consists in the novel features of construction and combination and arrangement, all of which will be fully described herein-after and pointed out in the claim.

In the drawings forming part of this specification, Figure 1 is a perspective view illustrating a carpet-stretcher constructed in accordance with my invention and in operation. Fig. 2 is a side elevation. Fig. 3 is a transverse section taken on the line $\alpha - \alpha$ of Fig. 2. Fig. 4 is a top plan view. Fig. 5 is a perspective view of the ratchet-faced bar connected to the toothed stretching-bar. Fig. 6 is a detail perspective view illustrating the central portion of said toothed stretching-bar.

In carrying out my invention I employ a wooden bar or strip A of any suitable size, said bar having teeth barbs or prongs A' arranged in the under face thereof for the purpose of gripping the carpet to be stretched. This bar A has a central recess or notch A² produced in the upper face thereof and extending nearly to the bottom of the same and in which the forward end of a longitudinal bar or strip B rests, said longitudinal bar having a barb or prong B' secured to the lower side of its rear end, which is adapted to be forced into the floor adjacent to the chair-board for the purpose of securely anchoring the stretcher. A metallic bar or plate C, essentially T-shaped in form, is secured to the upper side of the transverse bar

A, said bar or plate C resting and sliding upon the longitudinal bar B and having a series of ratchet-faced recesses or notches C' produced therein. A bifurcated lever D is pivotally connected to the bar B about midway its length, said bifurcated lever straddling the ratchet-faced bar C and carrying a pawl D', which is adapted to engage the ratchet-face C' of the said bar. The rear end of the ratchet-faced bar C is provided with lateral guides C², which are adapted to fit into the grooves B², produced in the sides of the bar B, and upon one side of the said bar B and directly below the grooves B² is the ratchet-faced projection B³, which is adapted to be engaged by the locking-pawl C³, pivotally connected to the bar C adjacent to its rear end.

In operation the parts are arranged as shown in Figs. 1 and 2, and the barb or prong B' is then forced into the floor adjacent to the chair-board. The teeth-prongs A' are forced into the carpet to be stretched and the hand-lever is pushed down toward the bar B. This action causes the ratchet-faced bar C to be moved rearwardly upon the bar B, carrying with it the toothed bar A, and the pawl C³ will be carried rearwardly and will drop into engagement with the next adjacent ratchet B². The lever is then again raised, so as to engage another one of the ratchet-faced recesses C' of the bar C, and is then forced down again, moving the toothed bar rearwardly, and these operations are continued until the carpet has been stretched to the desired extent, and it will be noted that at each rearward movement the locking-pawls C³ securely lock the parts against any return movement, thereby holding the carpet stretched after each operation of the hand-lever D.

It is obvious that the various parts may be constructed of any desirable material and may be of any size and shape desired so long as the relative arrangement of the parts is maintained, and it will also be understood that certain changes or alterations may be made without departing from the broad principle of my invention.

Having thus fully described my invention, what I claim as new, and desire to secure by Letters Patent, is—

In a carpet-stretcher the combination with a longitudinal bar having an anchoring point or barb and provided with a ratchet-face on one side of the transverse carpet-gripping bar, the T-shaped plate or bar connected to the carpet-gripping bar, and sliding upon the longitudinal bar, said T-shaped bar having a ratchet-face, a bifurcated hand-lever pivoted to the longitudinal bar, a pawl carried by the said lever adapted to engage the

ratchet-face of the T-shaped bar, and the locking-pawl carried at the rear end of the T-shaped bar and adapted to engage the ratchet-face upon the longitudinal bar for the purpose specified.

HENRY RIPLEY.
